US0D1047302S

(12) **United States Design Patent** (10) **Patent No.:** **US D1,047,302 S**
(45) **Date of Patent:** **** Oct. 15, 2024**

(54) **BIRD FEEDER**

(71) Applicant: **SHENZHEN HUAHANXING TECHNOLOGY CO; LTD**, Shenzhen (CN)

(72) Inventor: **Wenfeng Xue**, Shangrao (CN)

(73) Assignee: **SHENZHEN HUAHANXING TECHNOLOGY CO; LTD**

(**) Term: **15 Years**

(21) Appl. No.: **29/885,066**

(22) Filed: **Feb. 20, 2023**

(51) LOC (14) Cl. **30-03**

(52) U.S. Cl.

USPC **D30/124**; D30/126

(58) **Field of Classification Search**

(57) **CLAIM**

The ornamental design for a bird feeder, as shown and described.

DESCRIPTION

FIG. 1 is a first perspective view of a bird feeder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the bird feeder that form no part of the claimed design.

1 Claim, 8 Drawing Sheets
